UNITED STATES PATENT OFFICE.

EDWARD WESTON, OF NEWARK, NEW JERSEY.

DESIGN FOR A RESISTANCE-BOX.

SPECIFICATION forming part of Design No. 22,207, dated February 7, 1893.

Application filed September 10, 1892. Serial No. 445,567. Term of patent 14 years.

To all whom it may concern:

Be it known that I, EDWARD WESTON, of Newark, Essex county, New Jersey, have invented and produced a new and original Design for Resistance-Boxes, of which the following is a specification.

My design consists in the upper surface configuration of a resistance box. Upon said surface A appears a series of rectangular elevations, B, C, D, E, F, each elevation being in the shape of a parallelogram, and the said parallelograms appear with their elongated

sides parallel. In each of the elevations B, C, D, E, appear apertures, and in the elevation F appear pairs of apertures disposed in parallel lines.

I claim as my invention

The design for a resistance box substantially as herein shown and described.

EDWARD WESTON.
